RAY COFMAN, OF BLOOM TOWNSHIP, FAIRFIELD COUNTY, OHIO.

MARKER FOR CORN-PLANTERS.

1,311,318.

Specification of Letters Patent. Patented July 29, 1919.

Application filed February 24, 1919. Serial No. 278,621.

To all whom it may concern:

Be it known that I, RAY COFMAN, a citizen of the United States, residing at Bloom township, in the county of Fairfield and State of Ohio, have invented a certain new and useful Improvement in Markers for Corn-Planters, of which the following is a specification.

This invention relates to that type of marker which is carried on the end of an arm, the arm being pivoted on the rear of the planter frame so as to be shiftable from one side of the planter to the other. The object of the invention is to provide improved means for shifting the marker over without using the hand.

The invention is embodied in the example herein shown and described, the features of novelty being finally claimed.

20 In the accompanying drawing—

Figure 1 is a plan view illustrating the means as applied to a planter.

Fig. 2 is a vertical sectional view on the line II—II Fig. 1 looking up.

25 Fig. 3 is a diagrammatic view illustrating the principle involved.

In the views 5 designates the frame of the planter, said frame being supported by suitable carrying wheels 6 as usual.

30 7 designates a shaft suitably journaled longitudinally on the frame said shaft having affixed to its rear end one end of the marker arm 8 carrying at its other end the marker 9. Secured on the shaft 7 is a bevelled gear 10. Engaging the bevel gear 10 is a similar bevel gear 11 having a crank shaft 12 journaled in the frame, a supplemental piece 13 being added to the frame to support one of the ends of the crank 40 shaft.

14 designates the driver's seat. The gears 10, 11 and crank shaft 12 are so located as to be within operative range of the driver's foot and so that the driver can exert 45 considerable weight upon the crank or sufficient to raise the marker arm to nearly vertical position. The momentum of the rising arm will carry it beyond the vertical toward the opposite side of the planter. When the 50 marker arm thus passes the vertical it is important that its fall be resisted otherwise it might be broken. To provide for this the gears are so proportioned to each other that when the marker arm is in vertical position

the crank is at or about at its most depressed 55 position hence when the marker arm is falling from the vertical the crank is rising and against the rising crank the driver again imposes his weight and thereby resists undue rapidity in the descent of the marker. 60

The diagram Fig. 3 illustrates substantially proper relative positions of the marker, operating crank and gears. In this view the parts are designated the same as before except that the bevel gears which are 65 here represented in spur gear form are designated 10^a and 11^a.

With the construction as herein described it is unnecessary for the driver to let go of the reins to shift the marker. 70

The forms of the parts can be changed without departing from the invention as claimed.

What I claim is:

1. In a corn planter the combination of a 75 marker arm and a rotary shaft on which the marker arm is fixed, a foot-operated crank shaft, and gears connecting said shafts, said gears arranged and proportioned with respect to each other as to require movement 80 of the crank downward and beyond a vertical plane coinciding with that of the crank shaft to shift the marker from either side of the planter to the other, substantially as described. 85

2. In a corn planter the combination of a marker arm and a rotary shaft on which the marker arm is fixed, a foot-operated crank shaft arranged at right angles to the marker shaft, and gears connecting said shafts, said 90 gears arranged and proportioned with respect to each other as to require movement of the crank downward and beyond a vertical plane coinciding with that of the crank shaft to shift the marker from either side of the planter to the other, substantially as described. 95

3. In a corn planter, the combination of a marker arm and a rotary shaft on which the marker arm is fixed, a foot-operated 100 crank shaft and gearing between the shaft of the marker arm and the crank shaft to cause the marker arm to rise when the crank of the crank shaft is depressed and to cause said crank of the crank shaft to 105 rise when the marker arm falls.

RAY COFMAN.
